COLLAPSIBLE FILING DRAWER

Harry L. Fellowes, Chicago, Ill., assignor
 Bankers Box Company, Chicago, Ill., a corporation of Illinois

Application July 14, 1937, Serial No. 153,629

4 Claims. (Cl. 229—34)

My invention contemplates and provides a novel and advantageous collapsible filing drawer which may be fabricated very largely of paper board and which, when in erected assembly, is very strong, and of neat and sturdy appearance.

By the term "filing drawer," as herein used, is meant a drawer adapted to slide in and out of a drawer holding case and employed for day-to-day or transfer filing.

10 A salient object of the present invention is to provide a novel filing drawer which may be shipped folded flat and easily and quickly opened and secured in erected position by the user.

Another important object of the invention is 15 to provide a filing drawer which is strong, rigid, of pleasing appearance, and which may be manufactured at very low cost.

A further object of the invention is to provide 20 a filing drawer having a front higher than the sides, and which has novel means for adding strength and rigidity to the front.

These and other objects and advantages will 25 become apparent during the course of the following description.

25 In the accompanying drawings forming a part of this specification, and in which like numerals are employed to designate like parts throughout the same:

Fig. 1 is a plan view of a paper board blank 30 from which a filing drawer embodying this invention may be fabricated;

Fig. 2 is a right rear perspective view of the 35 drawer blank partially folded;

Fig. 3 is a left front perspective view of the 40 erected drawer with the bottom liner exploded out of the other parts of the drawer;

Fig. 4 is a longitudinal vertical sectional view 45 of the drawer taken in the direction of the arrows along the line 4—4 of Fig. 5;

Fig. 5 is a lateral vertical sectional view of the 50 drawer taken in the direction of the arrows along the line 5—5 of Fig. 4 with a portion of the inner front wall broken away to show the side flaps and reinforcing member;

Fig. 6 is a horizontal sectional view of the front 55 portion of the drawer taken in the direction of the arrows along the line 6—6 of Fig. 5;

Fig. 7 is a longitudinal vertical sectional view 60 through a portion of the back wall taken in the direction of the arrows along the line 7—7 of Fig. 3;

Fig. 8 is a plan view, on a reduced scale, of the 65 blank which forms the reinforcing member for the drawer front;

Fig. 9 is a plan view similar to Fig. 1 but show-

ing the blank for a shallower drawer and a modified construction preferable for shallow drawers;

Fig. 10 is a plan view of the blank for the reinforcing member for the drawer front of the form of Fig. 9;

Fig. 11 is a longitudinal medial section of the 5 front end of the drawer of the form of Fig. 9 showing the drawer front partially folded into position;

Fig. 12 is a transverse vertical section through 10 the drawer of Fig. 9 looking toward the inside face of the drawer front, with a portion of the return flap broken away, taken on the line 12—12 of Fig. 13 and comparable with Fig. 5; and

Fig. 13 is a vertical medial longitudinal section 15 taken on the line 13—13 of Fig. 12, comparable with the right hand side of Fig. 4 and like Fig. 11 except that it shows the drawer front completed.

The drawer consists of a flat sheet 10 cut and 20 scored to form a rectangular bottom 12 near the center of the blank, with side walls 14 and side wall extensions 16 on either side, a rear wall 18 and rear wall extension 20 at one end, and a front wall 22 and front wall extension 24 at the 25 other end of the bottom section 12.

The side walls 14 and side wall extensions 16 are provided with rearwardly extending flaps 26 and 28, respectively, and forwardly extending flaps 30 and 32, respectively. The above several 30 parts of the drawer are divided from each other by longitudinal parallel scores 34, 36, 38, and 40, and by lateral parallel scores 42, 44, 46, and 48. The scores 34 and 36 divide the bottom 12 of the drawer from the two side walls 14, while the 35 scores 38 and 40 divide the side walls 14 from the side wall extensions 16. The score 42 divides the bottom 12 from the rear wall 18, and also divides the rearwardly extending flaps 26 and 28 from the side walls 14 and side wall extensions, 16 respectively. The score 44 divides the front wall 22 and forwardly extending flaps 30 and 32 from the bottom 12, side walls 14, and side wall extensions 16, respectively. The score 46 separates the rear wall 18 from the rear wall 45 extension 20, while the score 48 separates the front wall 22 from the front wall extension 24.

The flaps 26, 28, 30, and 32 are separated from each other and from the front and back walls 22 and 18 by knife cuts 50 and 52 and by narrow 50 slots 54 and 56 along the longitudinal scores 34, 36, 38, and 40 extending inwardly to the lateral scores 42 and 44.

The length of the flaps 26, 28, 30, and 32 is slightly less than one-half the width of the front 55

and rear walls 22 and 18, so that when the drawer is folded, as will be later described, the ends of these flaps will closely approach each other, but will not overlap.

- 5 The dimensions of the rear wall 18 between the scores 42 and 46 is slightly greater than the height of the side walls 14, while a similar dimension of the front wall 22, i. e., between the scores 44 and 48, I prefer to make considerably greater.
- 10 The front wall is made higher than the side walls, so that when the drawer is in use the side walls will offer less interference to inserting and withdrawing papers from the drawer than would otherwise be true.
- 15 The front wall 22 has secured to its inner face a reinforcing member 58 which may be conveniently formed from two thicknesses of paper board secured together. Preferably the reinforcing member 58 is formed from the E-shaped blank of
- 20 Fig. 8 by folding the ends inwardly about the dotted score lines indicated. The reinforcing member 58 is T shaped, with the arms 60 of the T extending across the front wall 22 from side to side, while its top edge 62 is adjacent to the
- 25 score 48. The lower edges 64 of the arms 60 are spaced from the score 44 a distance equal to the height of the side walls 14, so that when the drawer is folded, the reinforcing member 58 will aid in supporting that portion of the front wall 22
- 30 which is above the side walls 14, and will also serve to engage the tops of the flaps 30 and 32 and secure them in proper position, as best shown in Fig. 5. The stem 66 of the T shaped reinforcing member 58 fits into reentrant right angles 68 and
- 35 70 formed in the front flaps 30 and 32, thereby distributing over a larger area the strain on the flaps caused by their attempting to move upwardly. This stem 66 also serves to give added rigidity to that portion of the reinforcing member 58
- 40 which extends above the side walls 14 and supports the top portion of the drawer front.

In erecting the drawer, the side walls 14 are bent upwardly perpendicular to the bottom 12, and the side wall extensions 16 turned inwardly 45 and downwardly against the side walls, so that the side walls and side wall extensions together form a double thickness wall for the drawer with a smooth turned edge uppermost. Next, the end flaps 28, 28, 30, and 32 are turned inwardly across 50 the ends of the drawer and enclosed within the end walls 18 and 22 and end wall extensions 20 and 24, which are folded in a manner similar to the folding of the side walls and side wall extensions. In folding the front wall and front wall 55 extension, care should be exercised to insure the proper fitting of the reentrant angles 68 and 70 around the stem 66 of the T shaped reinforcing member 58.

When the drawer is folded, properly located 60 holes 72 in the flaps are brought into alignment with holes 74 in the end walls and end wall extensions. In this position, screws 76 are inserted through each set of aligned holes 72 and 74 and secured by nuts 78. Because of the thickness of 65 the paper board, the portions of the end wall extensions 20 and 24 which are folded inside the drawer are provided with reentrant right angles 80 which are as long as the height of the side walls 14, and as wide as the thickness of the double

70 walls.

For the same reason, i. e., because of the thickness of the paper board, the flaps 28 and 32 at the ends of the side wall extensions 16 are slightly shorter, best seen in Fig. 1, than the flaps 28 and 75 30 at the ends of the side walls 14.

To strengthen the bottom 12 of the drawer, I prefer to add to the above a rectangular paper board bottom liner 82, cut to proper size, which is inserted into the drawer and pressed against the bottom 12. This bottom liner 82 also serves to urge the lower edges of the side wall extensions 16 tightly against the side walls 14, and thereby provides square interior corners 84 between the bottom of the drawer and its side walls.

To aid in withdrawing the above drawer from its case, a handle 86 is secured to the front of the drawer by means of nuts 88 and screws 90 passed through aligned holes 92, which are formed in the paper board during the manufacture of the drawer blank. To prevent the tendency of the screws 90 to pull through the paper board, these screws may be supplied with washers 94 beneath their heads. The passing of the screws 90 through the four thicknesses of paper board strengthens the drawer front as well as providing a convenient 20 method for attaching the handle 86.

In Figs. 9 to 13, inclusive, I have shown a shallower drawer of generally similar construction, but differing somewhat especially in the form and arrangement of the reinforcement for the 25 drawer front, this being preferable where the drawer is relatively shallow. In Figs. 9 to 13 the primed reference characters are to be understood as the same as or corresponding to the similarly numbered parts in the previous characters.

In the form of Figs. 9 to 13 I do not laterally interengage the reinforcing member 58' with the extensions 30' and 32'. The reinforcing member 58' takes the form of a simple straight-sided filler of double thickness interposed between the 35 upper edges of the extensions 30' and 32' and the bight formed by the front wall 22' and its return-folded extension 24'. The reinforcing member 58' is a narrow strip of a length twice the width of the drawer. The ends of the member 58' 40 are folded inwardly so that they abut at the center. The mating faces of the main body and the return-folded ends of the member 58' are glued together. The reinforcing member 58' is then glued to the inside face of the front wall 22' adjacent its double score 48'.

The drawer blank is folded up into its completed and assembled position in substantially the same manner as the first form. As shown in Figs. 11 and 13, as the front wall 22', carrying the reinforcing member 58', is swung up into vertical position, the reinforcing member assumes a position immediately above the extensions 30' and 32' and constitutes a filler of the same thickness as the overall thicknesses of the 55 extensions 30' and 32'. The completed and assembled drawer front thus consists throughout of four thicknesses of stock, to the exclusion of any hollows.

Fig. 9 shows the scorings 46' and 48' extended 60 across the extensions 26', 28', 30' and 32'. The scoring serves no useful purpose on the extensions. I have shown them, however, because in practice it is easier to extend the scoring across the extensions than to swing the extensions out 65 of the path of the scorer. This is a situation encountered where the height of the front or rear wall is less than half the width of the drawer.

It will be seen that filing drawers, when constructed in accordance with this invention, will have double thickness side and bottom walls and four thicknesses in the end walls. Also the tops of the drawer walls will all have turned edges, thereby providing a smooth surface. Thus, the 70 75

drawer is very strong, rigid, of neat appearance, and efficient in use, even though constructed largely of paper board at very low cost.

Although I have described a preferred embodiment of my invention, it should be understood that I contemplate that departures may be made therefrom, and that the scope of my invention is to be limited solely by the following claims.

I claim:

- 10 1. A file drawer comprising, a bottom wall; an end wall and side walls attached to said bottom wall; an end wall extension and side wall extensions attached to the end wall and side walls respectively; said end wall being higher than said side walls and having a member to reinforce the portion of said end wall above said side walls; and flaps attached to said side walls and side wall extensions, said flaps being in the same plane as said reinforcing member and enclosed between the end wall and end wall extension.
- 15 2. A file drawer comprising, a bottom wall; an end wall and side walls attached to said bottom wall; an end wall extension and side wall extensions attached to the end wall and side walls respectively; said end wall being higher than said side walls and having a member to reinforce the portion of said end wall above said side walls; flaps attached to said side walls and side wall extensions, said flaps being in the same plane as said reinforcing member and enclosed between the end wall and end wall extension; and means to reinforce the bottom of said drawer and hold said side wall extensions against said side walls; said means comprising a removable inner bottom.
- 20 3. A paper board file drawer comprising, a bottom wall; an end wall and side walls attached to said bottom wall, said end wall being higher than said side walls; a reinforcing member for said end wall, a portion of said reinforcing mem-
- ber substantially covering the inner surface of said end wall above said side walls; another portion of said reinforcing member fractionally covering the portion of said end wall below the tops of said side walls; end wall and side wall extensions attached to said end and side walls; flaps attached to said side walls and side wall extensions, and adapted to be enclosed between said end wall and end wall extension in the same plane as said reinforcing member, and means to reinforce the bottom of said drawer and hold said side wall extensions against said side walls, said means comprising a removable inner bottom.
- 25 4. A collapsed paper board filing drawer comprising an integral blank having a central bottom wall, side walls extending laterally from the side edges of the bottom, side wall extensions extending laterally from the outer edges of the side walls, flaps extending from the front and rear ends of the side walls and side wall extensions, a rear wall extending from one end of the bottom, a rear wall extension extending rearwardly from the rear wall, a front wall of greater height than the side walls and extending from the other end of the bottom, and a front wall extension extending forwardly from the front wall, the flaps being of a length substantially half the width of the bottom whereby, when the side walls are swung to vertical position and their extensions swung downwardly into contact with the side walls and the flaps swung inwardly to transverse vertical position, the ends of the flaps from the two sides substantially abut, and a reinforcing strip of length approximating the width of the front wall and adapted to fill the space above the front flaps and between the front wall and its extension when the drawer is assembled.

HARRY L. FELLOWES. 40
